UNITED STATES PATENT OFFICE.

ERWIN P. BANCROFT, OF BROOKLYN, NEW YORK, ASSIGNOR TO WESTERN ELECTRIC COMPANY, INCORPORATED, OF NEW YORK, N. Y., A CORPORATION OF NEW YORK.

PRINTING TELEGRAPHY.

Application filed December 31, 1921. Serial No. 526,244.

To all whom it may concern:

Be it known that I, ERWIN P. BANCROFT, a citizen of the United States, residing at Brooklyn, in the county of Kings, State of New York, have invented certain new and useful Improvements in Printing Telegraphy, of which the following is a full, clear, concise, and exact description.

This invention relates to telegraph systems.

An object of the invention is to provide a system whereby a plurality of telegraph messages originating at separate stations may be transmitted over a plurality of branch lines or extension circuits to main or central stations where synchronous multiplex apparatus is located for automatically and simultaneously transferring the code combinations of message impulses to a line connecting the central stations.

Another object is the provision of means associated with the synchronous multiplex apparatus at the central stations for providing a complete overlap between the selections received from the extension circuits or branch lines and those transmitted by the synchronous multiplex apparatus to the line connecting the central stations.

Another object is to provide in conjunction with the synchronous multiplex apparatus, means for providing a complete overlap between the selections received from the line connecting the central stations and those transmitted to the extension circuits or branch lines.

The invention provides synchronous multiplex and start-stop apparatus at the central stations with means associated therewith such as a plurality of groups of relays for providing a complete overlap between the selections received from the start-stop apparatus and those transmitted by the synchronous multiplex apparatus so that irrespective of what the phase relation between the start-stop and the synchronous multiplex apparatus is, the selections coming in on the start-stop apparatus will be directly transmitted to the multiplex apparatus providing, that the speed of the start-stop apparatus is equal to or slightly less than the speed of the multiplex apparatus. Likewise, according to one of the embodiments of the invention

there is provided intermediate the synchronous multiplex apparatus associated with the line conductor connecting the two stations and the start-stop apparatus which transmits the impulses received from the synchronous multiplex apparatus to the extension circuit, means such as a group of condensers and relays for providing a complete overlap between the selections received on the multiplex apparatus and those transmitted by the start-stop apparatus.

The invention is illustrated in the accompanying drawings which represent one embodiment of the invention and when arranged so that Fig. 1 is to the left of Fig. 2, a complete system is shown diagrammatically.

The invention, in general, comprises a branch office A which is connected with a main or central office B by an extension circuit or branch line 6, a central or main station C connecting with the main station B by a line conductor 7 equipped with duplex apparatus and a distant branch office D which, like branch office A, is connected with the associated central station C by an extension circuit 8.

At the branch office A there are located transmitting and receiving equipments E and F, respectively, being shown diagrammatically. The extension circuit 6 may be a pair of line conductors or a single line conductor equipped with duplex apparatus as illustrated in the drawings. Both of the central stations B and C are provided with receiving distributors G and H of the start-stop type to receive the code combinations of message impulses from the respective sub-stations or branch offices and transfer them to the multiplex synchronous distributors I and L also located at the offices B and C, respectively, through the instrumentalities of a plurality of groups of relays. Also located at the central offices are synchronous multiplex distributors K and M, each of which serve to receive the signaling impulses from the line conductor 7 connecting these two stations and transferring the same to the start-stop distributors N and R, respectively, through the instrumentalities of a series of condensers, and a group of relays which, according to the present invention, provide a

complete overlap between the selections received on the synchronous multiplex distributor and those transmitted to the extension circuits by the start-stop distributors associated therewith. Branch office D like branch office A is provided with a transmitting distributor P and a receiving distributor Q which serve their respective purposes. For the sake of simplifying the drawing, 10 the apparatus common to one channel has been shown in detail while that individual to the other channel has been shown schematically.

The transmitting equipment E comprises 15 an intermittently rotary distributor 10 having a brush arm 11 which carries a pair of brushes 12 and 13, which in turn, are arranged to make contact with rings 14, 15, 16 and 17. The outer ring 17 is divided into 20 a plurality of segments 18, 19, 20, 21, 22 and 23 which are connected with the respective contacts of a transmitter shown diagrammatically at 24. In order that the brush arm 11 will be stopped and released 25 once per revolution, a release magnet 27 is provided which is under the control of a start relay 28 which is controlled by a common contact on the transmitter shown 30 diagrammatically at 24. The transmitter 24 consists of a plurality of movable contacts 30, 31, 32, 33 and 34 which are connected to the respective segments forming the outer ring 17 of the distributor 10. Also in the transmitter 24 is a common contact 35 which, as previously stated, 35 controls the energization of the start relay 28. Although the transmitter 24 has been shown diagrammatically as a keyboard transmitter any well-known type of transmitter may be substituted therefor.

40 At the central office B there is shown a receiving distributor G of the start-stop type and a synchronously operated distributor I which has its continuous ring 95 connected to the apex of the ratio arms which 45 includes the receiving relay 99 forming a part of the duplex equipment associated with the line conductor 7. The line relay 99 responds only to incoming impulses and is non-responsive to outgoing impulses. Upon 50 the operation of the multiplex distributor I, this relay will not respond to impulses which may be transferred thereto from the start-stop distributor G.

The start-stop distributor G comprises an 55 outer ring 44 and an inner ring 40. Forming a part of the outer ring is a plurality of segments 47, 48, 49, 50, 51 and 52, each of which corresponds to respective ones of the segments on the transmitting distributor 10. 60 By the proper orientation of these segments and inasmuch as they are smaller than the transmitting segments of the transmitting distributor 10, the central portion of the signaling impulses transmitted over the extension circuit 6 to the line relay 37 will be

picked up for each segment of the landing face at the branch office A. The distributor G also comprises a brush arm 41 carrying a brush 42 which is held against rotation by a release latch under the control of a release magnet 39.

Interposed between the start-stop distributor G and the multiplex or synchronously operated distributor I are a plurality of groups of storing relays which are 70 operable in accordance with the signals transmitted and controlled by a series of transfer relays under the control of both the start-stop distributor G and the multiplex I. These sets of relays provide a complete 75 overlap between the selections received from the start-stop distributor G and those transmitted over the line 7 by the multiplex distributor I irrespective of what the phase relation is between the brush arm of the 80 start-stop distributor G and the brush arm of the multiplex distributor I providing, of course, that the speed of the brush arm of the start-stop distributor is equal to or slightly less than the speed of the brush arm of the multiplex distributor I. The relays 56, 57, 58, 59 and 60 forming the first 85 group of storing relays are connected directly to the receiving segments forming the outer ring 44 of the distributor G and will 90 be energized in accordance with the operation of relay 38. The second set of storing relays comprises relays 70, 71, 72, 73 and 74 which are under the control of the corresponding relays of the first set, the energizing 95 circuits of which are completed through the right-hand armature of relay 66, which, as more clearly described hereinafter, is controlled through contacts of the relay 61 as well as the segments on the multiplex distributor I. The third set of storing relays 100 comprises the relays 76, 77, 78, 79 and 80 which are under the control of the first set of relays and are also locked up upon their energization. Thus, after a set of impulses 105 has been transmitted from the distributor G to the first set of storing relays, the transfer relay 65 is energized under the joint control of the start-stop distributor G and the multiplex distributor I for transferring the 110 impulses stored on the first set to the relays forming the second set. Accordingly, the third set of storing relays will be energized 115 depending upon the energization of the relays of the second set. All of the relays will 120 be locked up through their own contacts following their initial energization so that after once being energized are maintained energized independent of the impulses coming in on the extension circuit 6. After the 125 impulses stored in the first set of storing relays have been cleared out the next succeeding message impulses may be stored in the storing relays 56 to 60, inclusive. After the second set of storing relays 70 to 74, inclu- 130

sive, are energized they establish through their contacts, energizing circuits for the corresponding ones of the storing relays of the third set, which, like the second set, are 5 locked up and retained in such position until released by a relay under the control of the multiplex distributor I. It is through the contacts of the third set of storing relays that the polarity of the impulses corresponding to the various characters is varied.

In order that the impulses will be transferred from the respective parts of the circuit so that no mutilation of the signals will result, such transfer is under the joint control of the start-stop distributor G and the synchronous multiplex distributor I, as will be more clearly described hereinafter.

The apparatus just described constitutes the equipment located at the central or main 20 station B which serves to transmit impulses from the branch office A to the line conductor 7 and thence to the central office C from which message impulses are transmitted to the distant branch office D.

25 The apparatus at the central office C which receives the signals transmitted from the transmitting apparatus located at the central office B comprises a multiplex distributor M and a distributor of the start-stop 30 type R. The multiplex distributor M comprises, among other parts, a continuous ring 113 and an outer ring which is divided into a plurality of segments 107, 108, 109, 110, 111 and 112. Like the distributor I a 35 continuously revolving brush arm 102 carrying brushes 103 and 104 is also provided. Connected to the smaller segments forming a part of the outer ring are the terminals of a set of condensers 115, 116, 117, 118 and 40 119 which serve in combination with a series of transfer relays 120, 121 and 114 and a set of storing relays 122, 123, 124, 125 and 126 to provide a complete overlap between the selections received on the multiplex distributor M and those transmitted over the 45 extension circuit 8 by the start-stop distributor R. The condensers 115 to 119 inclusive, are charged in accordance with the operation of the line relay 101 upon the passage of the brush 104 over the corresponding segments. Following the passage of the brush 104 over segment 111 and the engagement of this brush with the segment 50 105, an energizing circuit is established for the transfer relays 120, 121 and 114 which establish through their contacts a discharge circuit for the condensers including the windings of the storing relays 122, 123, 124, 125 and 126 which will be energized in accordance with the condensers which have been previously charged.

55 The start-stop distributor R comprises an outer ring divided into a plurality of smaller segments 132, 133, 134, 135, 136 and 137. 60 The first five of these segments are connected

to the upper armatures of relays 122, 123, 124, 125 and 126 which, upon their energization, are locked up whereby the armatures remain in the position set until released due to the operation of relay 140 70 which controls the locking circuit of these relays. For bridging the outer ring of the distributor R with the inner ring 138, the distributor has a brush 130 carried by a brush arm 128 which is normally held 75 against rotation by a latch under the control of a release magnet 131. The release magnet 131 is controlled by relay 127, which in turn is energized in accordance with the energization of any one of the storing relays 80 122 to 126, inclusive. Thus, upon the energization of any one of these relays, an energizing circuit for relay 127 is completed thereby establishing an energizing circuit 85 for the release magnet 131 which permits the rotation of the brush arm 128.

The receiving equipment at the branch office D comprises a receiving printer diagrammatically shown at 155 which comprises the usual selecting magnets 156, 157, 158, 159 and 160 and the printing magnet 168. The respective magnets have their windings connected to the segments 161, 162, 163, 164 and 165 forming a part of the outer ring of the distributor Q. The distributor Q like the distributor G has a brush arm 147 carrying a brush 148 which is arranged to bridge the segments forming a part of the outer ring with the segments 154, 166 and 152 for controlling the energization of the respective ones of the selecting magnets depending upon the energization of relay 151 which is in turn controlled by the line relay 146 connected to the extension circuit 8.

Inasmuch as the apparatus associated with the other channel of the system is identical to the equipment just described, further description thereof is considered unnecessary here. However, the rectangles designated by the characters S and T represent the equipment intermediate the distributors G and I and H and R, respectively, which, as previously described, are shown diagrammatically for the sake of clarifying the drawings.

115 The operation of the equipment just described is as follows: Assuming, for the sake of clearness, that the branch office A desires to communicate with the branch office D, the transmitter 24 will be operated to set 120 up a particular combination depending upon the message desired to be transmitted. Let it also be assumed that it is desired to transmit a character in which contacts 30, 32 and 34 of the transmitter 24 are actuated to close 125 their respective contacts. As previously described, upon the operation of the transmitter 24, contact 35 will be closed for causing the energization of start relay 28, the energizing circuit of which extends from 130

battery through the left-hand winding thereof, contact 35, segment 15, brush 13 and segment 14 of the transmitting distributor 10 to ground. The start relay 28 is 5 thereupon energized and is locked up over a circuit under the control of the brush 13. Upon the energization of the start relay 28, an energizing circuit is established for the release magnet 27 which, in operating, withdraws the release latch under its control 10 from engagement with the brush arm 11, which is thereupon free to rotate whereupon the brush 12 consecutively completes circuits extending from the segments 18 to 22 inclusive, and the contacts of the transmitter 24, which have been operated through the winding of the pole changing relay 29. The pole changing relay 29 is energized upon the passage of the brush 12 over a segment to which 15 one of the closed contacts of the transmitter 24 is connected for applying to the line 6 an impulse of a polarity corresponding to that normally applied thereto. However, the instant the brush 12 passes off the segment 20 23, an open circuit condition is established whereby the pole changing relay 29 reverses the position of its armature, connects the positive source of current with the apex of the ratio arms in which the receiving relay 36 is connected, but which does not respond to outgoing impulses. The receiving relay 37 located at the central office B does, however, respond to such changes in 25 polarity and reverses the position of its armature whereby the energizing circuit of the relay 38 is broken. Consequently, the energizing circuit for the release magnet 39 of distributor G is established. The release magnet 39 being energized, the brush arm 41 is thereby released for rotation owing to the withdrawal of the release latch under its control. Contact 30 of the transmitter 24 being closed, an energizing circuit for the pole changing relay 29 is established upon 30 the passage of the brush 12 over segment 18 of the transmitting distributor 10, thus connecting the negative pole of the battery with the line conductor 6, and consequently, causing the reversal of the armature of the receiving relay 37 to the position shown in the drawing, which in turn, causes the energization of relay 38. The closure of the front contact of relay 38 establishes upon 35 the passage of the brush 42 over segment 47, an energizing circuit for relay 56 extending from battery through the armature and alternate contact of relay 38, segment 45, brush 42, segment 47 of the distributor G, and the winding of relay 56, and the contact and armature of relay 62 to ground. Upon the closure of the right-hand armature and contact of this relay, a locking circuit is established therefor, extending 40 from battery through the left-hand contact and armature and winding thereof, and the

contact and armature of relay 62 to ground. Contact 31 of the transmitter 24 being open, the pole changing relay 29 is caused to reverse the position of its armature upon the passage of the brush 12 over segment 19 to which contact 31 of the transmitter 24 is connected. Similarly, the receiving relay 37 at office B reverses the position of its armature, and consequently causes the de-energization of relay 38. Thus, upon the passage of the brush 42 over segment 48 of the distributor G, relay 57 will not be energized. Contacts 32 and 34 of the transmitter 24 being closed, a condition similar to that described in connection with contact 30 will be established for causing the energization of relays 58 and 60 in accordance with the energization of relay 38 upon the passage of the brush 42 over the segments to which these relays are connected. Relay 59 will, however, not be energized owing to contact 33 of the transmitter being open so that an open circuit condition is established upon the passage of the brush 42 over the segment individual thereto. 45

Just prior to the completion of the cycle of rotation of the brush arm 41 of the distributor G, an energizing circuit is established for relay 61 extending from battery through segment 46, brush 42, segment 52 of the distributor G, winding of relay 61 and the contact and armature of relay 62 to ground. A locking circuit is established for relay 61 upon the closure of its left-hand contact extending from battery through the left-hand armature and contact and winding of this relay, and the contact and armature of relay 62. Upon the closure of the right-hand contact of relay 61, an energizing circuit is conditioned for relay 66, but which will not be completed until relay 63 is energized, which, in turn, is under the control of relay 64 which is of the slow-to-operate type. The brush 88 of the multiplex distributor I in passing over segment 96 establishes an energizing circuit for clear out relay 75 which extends from battery through ring 98, brush 88, segment 96 of the distributor I and the winding of clear out relay 75 to ground. This relay, as previously described, controls the locking circuit of the third group of storing relays 76 to 80, inclusive, so that upon the energization of this relay, any of these relays which might have previously been energized will be released and restore their armatures to the position shown in the drawing. Following the passage of the brush 88 off of segment 96, this brush engages segment 97 which establishes an energizing circuit for transfer relay 65 extending from battery through segment 98, brush 88, segment 97, armature and contact of relay 67, right-hand winding of relay 65 and the right-hand armature and contact of relay 64 to ground. Relay 65 thereupon at- 50 55 60 65 70 75 80 85 90 95 100 105 110 115 120 125 130

tracts its armatures and establishes through its left-hand armature and contact a locking circuit for itself, while at its right-hand contact it establishes an energizing circuit for the 5 third set of storing relays depending upon the energization of the relays of the second set. Should any of the relays of the second set be energized upon the energization of relay 65, an energizing circuit for the 10 corresponding relay of the third set will be established over a circuit extending from battery through the right-hand armature and contact of relay 65, right-hand armature and contact of the energized relay of the 15 second set, right-hand winding of the corresponding relay of the third set, and the contact and armature of clear out relay 75 to ground. As previously described, upon the energization of the relays of the third 20 set, a locking circuit is established therefor, and they will be held energized until the energization of clear out relay 75 upon the passage of the brush 88 over segment 96. Relay 65 in closing its left-hand contact also 25 establishes an energizing circuit for relay 64 which, however, as previously described, is of the slow-to-operate type and does not operate during the period which the relay 65 is transferring the impulses stored in the relays 30 70 to 74 from the second set of storing relays to the relays 76 to 80, forming the relays of the third set. However, upon the energization of relay 64, the holding circuit of the relays of the second set is broken at 35 its right-hand armature, whereupon any of the relays of this set which happen to be energized will be released, while at its left-hand contact an energizing circuit is established for relay 63 extending from battery, 40 armature and contact of relay 64, winding of relay 63, winding of relay 67 and the contact and armature of relay 62 to ground. Relay 67 in energizing opens at its contact the initial energizing circuit of relay 65, thus 45 preventing the energization of this relay upon the subsequent passage of the brush 88 over segment 97 providing the impulses have not been previously transferred to the respective sets of storing relays. Relay 63 in 50 closing its right-hand contact establishes a locking circuit for itself while at its left-hand contact an energizing circuit for relay 66 is established which conditions an energizing circuit for relay 62 and which is later 55 completed upon the deenergization of relay 64. Relay 66 also establishes an energizing circuit for the relays of the second set of storing relays corresponding to the relays of the first set which have been previously 60 energized. The energizing circuit for the relays of the second set extends from battery through the right-hand armature and contact of relay 66, right-hand contact and armature of the relay energized of the first 65 set, right-hand winding of the correspond- ing relay of the second set and the armature and contact of relay 64 which releases its armature upon the deenergization of relay 65, which, in turn, is released upon the energization of relay 64. The impulses stored 70 in the first set of storing relays will thus be transferred to the second set of storing relays which will be energized in accordance therewith and lock up until subsequently released due to the energization of relay 64 as 75 previously described. Upon the deenergization of relay 64, relay 62 is energized whereby the locking circuit of the first set of storing relays 56 to 60 and that of relay 61 is open for causing the restoration of 80 these relays to normal so that the next succeeding group of impulses may be stored in the storing relays 56 to 60 regardless of whether those stored in the other sets of 85 storing relays have been cleared out.

Relays 56, 58 and 60 being energized in the manner previously described, relays 70, 72 and 74 of the second set of storing relays will be energized upon the energization of relay 66. Relays 70, 72 and 74 upon closing their right-hand contacts conditions an energizing circuit for the relays of the third set and which is later completed upon the energization of relay 65 under the control of 90 the synchronous multiplex distributor I. The relays 57 and 59 not having been energized for the particular selection chosen remain in the position shown in the drawing. Consequently, the corresponding relays of 95 the second and third sets will remain deenergized. Relays 76 and 78 upon closing their right-hand alternate contacts connects the positive pole of the battery with segments 94 and 92 of the distributor I, respectively, while relay 80 connects the negative pole of 100 the battery with segment 90. Upon the passage of the brush 89 of the multiplex distributor I over the respective ones of the segments to which the armatures of the relays of the third set are connected, a polarity of battery depending upon the energization of the storing relays 76 to 80 will be applied to the apex of the ratio arms to which the receiving relay 99 is connected, and thence over the line conductor 7 to the central station C. The brush 89 in passing over segment 94 to which the armature of storing relay 76 is connected, an impulse of 105 a positive polarity will be transmitted to the central station C which passes through the armature of the receiving relay 101 for causing the reversal of its armature. The negative pole of the battery associated with the contacts of this relay is thereupon connected with the ring 113 of the distributor M so that 110 upon the passage of the brush 104 over the segment to which the condenser 115 is connected, this condenser will be charged over a circuit extending from battery through 115 the upper contact and armature of relay 101, 120

125 130

ring 113, brush 104, segment 107 of the distributor M and the condenser 115 to ground. As the brush arm 87 continues to rotate conditions depending upon the position of the 5 armatures of the storing relays 76 to 80 inclusive, will be set up for causing the corresponding positioning of the armature of receiving relay 101 at the central office C. Thus, upon the passage of the brush 104 10 over the segments to which the condensers 116, 117, 118 and 119 are connected, these condensers will be charged depending upon the energization of the storing relays of the third set of storing relays located at the central office B. For the particular selection 15 chosen, condensers 117 and 119 will be charged over circuits similar to that described in connection with condenser 115. The brush 103 upon passing over segment 105 establishes an energizing circuit 20 for the transfer relays 120, 121 and 114, the energizing circuit of which extends from battery through the windings of these relays in series, segment 105, brush 103 and 25 ring 106 to ground. These relays establish through their contacts a discharge circuit for the condensers through the upper winding of the storing relays 122 to 126. Condensers 115, 117 and 119 having been 30 charged, a discharge circuit therefor will be established upon the closure of the contacts of the transfer relay 120, 121 and 114 extending from the terminal of the condenser through the upper winding of the 35 corresponding storing relays and the armature and contact of the transfer relay to the other terminal of the condenser. For the particular selection chosen relays 122, 124 and 126 will be energized which upon 40 closing their lower armature and contacts establishes a locking circuit extending from battery through the armature, lower contact and winding thereof, contact and armature of relay 140 and the winding of relay 45 127 to ground. Relay 127 is also energized over the circuit just traced.

Following the passage of the brush 88 50 over segment 90 of the multiplex distributor I, this brush engages segment 96 whereupon an energizing circuit is established for clear out relay 75 so that upon the energization of this relay the locking 55 circuit for relays 76, 78 and 80 is broken thereby restoring these relays to the position shown in the drawing.

Should the brush 88 of the multiplex distributor I pass over segment 97 prior to the 60 passage of the brush 42 over segments 46 and 52 of the distributor G, the completion of the energizing circuit of relay 63 will be 65 prevented due to the fact that the relay 61 is at this time not energized. Thus, upon the continued rotation of the brush arm 87 no mutilation or piling up of the signals will 70 be caused owing to the energization of the

respective ones of the transfer relays for transferring the impulses from one set of storing relays to the next and nothing will occur except the transmission of a blank signal over the line conductor 7, following the 70 opening of the locking circuit of the relays forming the third set of storing relays. The transmission of a blank signal will have no effect on the printing mechanism at the branch office D. 75

Upon the energization of relay 127 an energizing circuit for the release magnet 131 is established extending from battery through the contact and armature of this relay, winding of release magnet 131, segment 143, brush 129 and segment 141 to ground. Release magnet 131 upon being energized withdraws its release latch from engagement with the brush arm 129 thereby permitting the rotation thereof. The brush 80 130 carried by the brush arm 139 consecutively connects the segments 132, 133, 134, 135 and 136 which are connected with the respective armatures of the storing relays 122 to 126 in circuit with the winding of 85 the pole changing relay 142. Prior to the engagement of the brush 130 with the segment 132, and upon the passage of this brush off of segment 137, pole changing relay 142 is deenergized thereby impressing on the extension circuit 8 an impulse of a positive polarity which, upon being received at the branch office D, causes the reversal of the armature of receiving relay 146. Relay 146 in reversing the position of its armature 90 causes the deenergization of relay 151, which, in turn, closes through its back contact an energizing circuit for release magnet 150 of the distributor Q, thus releasing the brush 95 arm 137 for rotation. 100

Upon the passage of the brush 130 over segment 132 and owing to the fact that the storing relay 122 is energized for the particular selection chosen, an energizing circuit is established for the pole changing relay 142 extending from battery through ring 138, brush 130, segment 132 of the distributor R, upper armature and contact of relay 122 and the winding of pole changing relay 142 to ground. The closure of such a circuit causes the energization of the pole changing relay 142 which impresses on the extension circuit 8 an impulse of a negative polarity for causing the reversal of the position of the armature of receiving relay 146 or to the position shown in the drawing, 110 consequently causing the energization of relay 151. Relay 151 being now energized upon the passage of the brush 148 over segment 161, selecting magnet 156 connected to this segment will be energized over a circuit extending from battery through the winding of this magnet, segment 161, brush 148, ring 154 and the alternate contact and armature of relay 151 to ground. The 115 120 125 130

movement of the selecting bar under the control of this magnet will be effected at this time. The brush 129 in passing over segment 133 and inasmuch as storing relay 123 is deenergized causes the pole changing relay 142 to reverse the position of its armature and impress on the extension circuit 8 an impulse of a positive polarity. Similarly, upon the passage of the brush 148 over segment 162 to which the selecting magnet 157 is connected, an open circuit condition is established owing to the fact that the receiving relay 146 has reversed the position of its armature, and in turn caused the deenergization of relay 151. Conditions similar to that just described for selecting magnet 156 will be established upon the passage of the brush 148 over segments 163 and 165, respectively, for causing the energization of the corresponding selecting magnets 158 and 160 of the receiving printer 155. However, since the storing relay 125 is not energized for this selection no effect will be produced by the selecting magnet 159 upon the passage of the brush 148 over segment 164 to which this selecting magnet is connected.

Following the passage of the brush 148 off the segment 165 and the passage thereof over segments 168 and 167, a circuit is completed extending from battery through the winding of printing magnet 168, segments 167, brush 148 and segment 166 to ground. Thus, the signals transmitted from the branch office A will be recorded on the receiving printer 155 at the branch office D over one channel of the line conductor 7 equipped for duplex operation.

Just prior to the completion of the cycle of rotation by the brush arm 128, segment 139 is bridged with segment 141 by the brush 129 for causing the energization of clear out relay 140 which not only causes the deenergization of relay 127 but also opens the locking circuit of the storing relays 122, 124 and 126 which thereupon deenergize. Likewise, upon the engagement of the brush 130 with the segment 137 an energizing circuit is established for the pole changing relay 142 which impresses upon the extension circuit 8, an impulse of a negative polarity for causing the relay 146 at the branch office D to position its armature to that shown in the drawing thereby causing the energization of relay 151.

It is apparent from the previous description that the present invention provides through the instrumentalities of means intermediate the distributor mechanisms at the central offices, a system in which signaling impulses are transmitted over the main line at a speed within predetermined limits.

While the transmitting mechanism must necessarily be operated at a speed within such limits, on the other hand the receiv-

ing mechanism associated with the extension circuit at the distant station is operated at a speed in excess of the speed at which signals are transmitted over the main line.

Although the invention has been illustrated in connection with a system where code combinations of message impulses originating at a branch office are transferred to a main or central office at which synchronous printing telegraph apparatus is located and thence over a conductor equipped for duplex operation to the second central or main station having equipment similar to that first referred to from which it is transferred over an extension circuit to a distant circuit, it is, of course, obvious that the invention may be readily applied to other types of system without departing from the spirit and scope of the invention.

What is claimed is:

1. A telegraph system comprising a main line, a plurality of branch lines, means interconnecting said main and branch lines, transmitting and receiving mechanisms associated with said branch lines, means for transmitting impulses over said main line at a speed within predetermined limits, means for controlling the operation of the transmitting mechanism independently of the receiving mechanism at a speed within such predetermined limits, and means for operating said receiving mechanism at a speed slightly in excess of the maximum limit at which signals are transmitted over the main line.

2. A telegraph system comprising a main line, a plurality of branch lines, means interconnecting said main and branch lines, intermittently operable transmitting and receiving mechanisms associated with said branch lines, means for transmitting impulses over said main line at a speed within predetermined limits, means for controlling the operation of the transmitting mechanism independently of the receiving mechanism at a speed within such predetermined limits, and means for operating said receiving mechanism at a speed slightly in excess of the maximum limit at which signals are transmitted over the main line.

3. In a printing telegraph system, a line conductor connecting two central stations, synchronous multiplex telegraph apparatus located at each of said central stations, extension circuits extending from said central stations, intermittently operable apparatus associated with each of said extension circuits, and means for operating said intermittently operable apparatus independently of said multiplex apparatus.

4. In combination, a plurality of central stations connected by a line conductor, synchronous multiplex apparatus located at said central stations and connected to said

line conductor, a plurality of branch offices inter-connected with said central stations by extension circuits, intermittently operable apparatus associated with said extension circuits and located at said central stations, means for controlling the operation of said intermittently operable apparatus independently of said synchronous multiplex apparatus and means associated with the apparatus at the central stations for providing a complete overlap between the selections received from an extension circuit and those transmitted to the main line and between the selections received from the main line which are subsequently transmitted over an extension circuit.

5. In combination, a plurality of central stations connected by a line conductor, synchronous multiplex apparatus located at said central stations and connected to said line conductor, a plurality of branch offices interconnected with said central stations by extension circuits, intermittently operable distributing mechanism associated with said extension circuits and located at the central stations, means for controlling the operation of said intermittently operable apparatus independently of said synchronous multiplex apparatus, means intermediate the intermittently operable distributing mechanism and the multiplex apparatus for providing a complete overlap between the selections received on the intermittently operable distributing mechanism and those transmitted by the multiplex apparatus, and means intermediate the multiplex apparatus and the intermittently operable distributing mechanisms located at the other station for providing a complete overlap between the selections received on the multiplex apparatus and those transmitted to the extension circuits through the instrumentalities of the intermittently operable distributing mechanism.

45. 6. In combination, a plurality of central stations connected by a line conductor, synchronous multiplex apparatus located at said central stations and connected to said line conductor, a plurality of branch offices interconnected with said central stations by extension circuits, intermittently operable distributing mechanism associated with said extension circuits and located at the central stations, means at each of the central stations connected intermediate the intermittently operable distributing mechanism and the multiplex apparatus for providing a complete overlap between the selections received on the intermittently operable distributing mechanism and those transmitted by the multiplex apparatus comprising a plurality of groups of storing relays under the joint control of the intermittently operable distributing mechanism and the multiplex apparatus, and a series of electrostatic

means and a group of storing relays at the other station for providing a complete overlap between the selections received on the multiplex apparatus and those transmitted to the extension circuits through the instrumentalities of said intermittently operable distributing mechanism. 70

7. In combination, a line conductor, synchronous multiplex apparatus connected thereto, an extension circuit, intermittently operable apparatus connected to said extension circuit, means for releasing said intermittently operable apparatus independently of such synchronous multiplex apparatus and means intermediate said multiplex and intermittently operable apparatus for providing a complete overlap between the selections received from said multiplex apparatus and those transmitted by said intermittently operable apparatus. 75

8. In combination, a line conductor, synchronous multiplex apparatus connected thereto, an extension circuit, intermittently operable apparatus connected to said extension circuit, and means comprising a group of electrostatic means and a set of relays for providing a complete overlap between the selections received from the multiplex apparatus and those transmitted by said intermittently operable apparatus. 80

9. In combination, a main line, synchronous multiplex apparatus connected thereto, intermittently operable distributing mechanism associated with said multiplex apparatus, means comprising a group of electrostatic means and a set of relays for providing a complete overlap between the selections received on the multiplex apparatus and those transmitted by the intermittently operable distributing mechanism, and means controlled by said multiplex apparatus for transferring the effects of said electrostatic means to said relays. 90

10. In combination, a main line, synchronous multiplex apparatus connected thereto, intermittently operable distributing mechanism associated with said multiplex apparatus, and means comprising a group of condensers and a set of relays for providing a complete overlap between the selections received on the multiplex apparatus and those transmitted by the intermittently operable distributing mechanism, and a group of relays controlled by said multiplex apparatus for establishing a discharge circuit for said condensers to said set of storing relays whereby said relays are energized in accordance with the condensers which have previously been charged. 110

11. In combination, a line conductor, synchronous multiplex apparatus connected thereto, an extension circuit, start-stop distributing mechanism associated with said extension circuit, means intermediate said multiplex apparatus and said start-stop distrib- 120

uting mechanism comprising a group of condensers and a set of relays for providing a complete overlap between the selections received on the said multiplex apparatus and those transmitted by said start-stop distributing mechanism, and means operated upon the energization of any one of said relays

for causing the release of said start-stop distributor.

In witness whereof, I hereunto subscribe my name this 30th day of December A. D., 1921.

ERWIN P. BANCROFT.
